[57] CLAIM

The ornamental design for a table base, as shown and
described.

DESCRIPTION

FIG. 1 is an elevational view of a table base showing
one of the four identical sides of my design;

FIG. 2 is a top plan view;

FIG. 3 is a bottom plan view; and

FIG. 4 is a perspective view thereof.

The table top depicted in broken lines in FIG. 1 has
been shown for illustrative purposes only.
